CLAIM

The ornamental design for a speakerphone, as shown and described.

DESCRIPTION

FIG. 1 is a perspective view of a first embodiment of a speakerphone, showing our new design;

FIG. 2 is an enlarged view of the portion 2-2 indicated in FIG. 1;

FIG. 3 is a front elevational view of the Speakerphone of FIG. 1;

FIG. 4 is a rear elevational view thereof;

FIG. 5 is a right side elevational view thereof;

FIG. 6 is a left side elevational view thereof;

FIG. 7 is a top plan view thereof; and

FIG. 8 is a bottom plan view thereof;

FIG. 9 is a perspective view of a second embodiment of a speakerphone, showing our new design;

FIG. 10 is a front elevational view thereof;

FIG. 11 is a rear elevational view thereof;

FIG. 12 is a right side elevational view thereof;

FIG. 13 is a left side elevational view thereof;

FIG. 14 is a top plan view thereof; and,

FIG. 15 is a bottom plan view thereof.

The broken lines consisting of a long dash and two short dashed depict reference to the enlargement shown in FIG. 2 and form no part of the claim.

All other broken lines depict portions of the speakerphone that form no part of the claimed design.

1 Claim, 15 Drawing Sheets
